BEVERAGE DISPENSER

James L. Hvale, Chicago, Ill., assignor to Ekco Products Company, Chicago, Ill., a corporation of Illinois

Application July 21, 1955, Serial No. 37,070

Term of patent 14 years

(Cl. D44—21)

Fig. 1 is a perspective view of a beverage dispenser showing my new design.

Fig. 2 is an enlarged top plan view thereof.

Fig. 3 is an enlarged side elevation.

Fig. 4 is an enlarged front elevational view.

I claim:

The ornamental design for a beverage dispenser, as shown.
